FLUONIC CONTROL CIRCUIT USEFUL WITH SEWING MACHINES

Robert C. Brandriff, Williamstown, and Charles G. Pick-
ett, Dover, N.J., assignors to The Singer Company,
New York, N.Y., a corporation of New Jersey

Filed Mar. 8, 1966, Ser. No. 532,708
5 Claims. (Cl. 112—218)

This invention relates in general to a fluonic control circuit, and in particular to a fluonic circuit for controlling the modulation of a fluid pulse train.

In a presently preferred environment for the invention, the circuit is employed to monitor the rate of thread consumption of an industrial sewing machine, whereby when such rate is either too low or too high, an alarm or other control unit is excited. The circuit of the invention preferably—though not necessarily—is adapted to receive a fluid pulse train wherein the durations of the pulses therein are all substantially constant, wherein the spacings between the pulses of such train substantially constant, and wherein the time-lengths of such durations and spacings are controllable. When the pulse durations and spacings of such train are substantially equal in time to respective reference time periods, the effective output of the instant control circuit is made to be zero; when such durations and spacings are greater or less in length of time than their respective reference time periods, the circuit is made to produce an output the time integral of which is a signal level that is proportional to the departures in length of time of such durations, and spacings, from their reference time periods. By providing a detector unit responsive to a predetermined level of the time integral signal, modulation of the pulse train may be so maintained that the effective circuit output (and the time integral signal) is always kept desirably at zero.

In adapting the circuit of the invention for use as a monitor for the rate of thread consumption of an industrial sewing machine, the following factors obtain: A broken needle thread causes the sewing machine consumption rate thereof to cease, whereas a broken bobbin thread causes the consumption rate of the needle thread to decrease. By providing a pulley having, for example, spokes that are substantially equisized with the spacings therebetween, and by directing a thin steady stream of air perpendicular to and at such spokes, a pulse train of air pressure pulses is had if the pulley is rotated by means of the consumable thread, and if the pulley is of sufficient mass to filter the periodic demand for thread by the sewing machine. A high rate of needle thread consumption effects pulse durations and spacing that are minimal; a low rate of needle thread consumption effects pulse durations and spacings that are substantial. Hence, by adapting the circuit of the invention to provide an effective output the time integral of which is zero only when the pulley rotational speed is representative of a sewing machine that is functioning properly and consuming needle thread at a normal or reference rate, then monitoring of the operation of such sewing machine, and of its thread consumption, is attained.

In relating the present invention to the prior art, reference should be had to application Ser. No. 510,227, which is assigned to the instant assignee. As disclosed in such application, the nature of the pulley-produced pulse train required therein is substantially limited to equisized pulse durations and pulse spaces, and further that a pair of time delay units are needed for circuit tuning purposes. Both limitations of the prior art are obviated by the present invention, as will be described hereinafter.

An object of the invention is to provide a fluonic circuit for use in so controlling the modulation of a fluid pulse train that the durations of and the spacings between ad-

2

jacent pulses thereof are timewise substantially equal to respective reference time periods.

Another object of the invention is to provide a fluonic circuit responsive to produce a control output signal when the durations and spacings of pulses in a received train of fluid pulses are not, in length of time, the same substantially as respective reference time periods.

Another object of the invention is to provide a fluonic circuit for controlling the modulation of a train of air pulses.

Another object of the invention is to provide a fluonic circuit for use in monitoring the rotary speed of an element.

Another object of the invention is to provide apparatus for use in monitoring thread consumption by a sewing machine or similar instrumentality.

Another object of the invention is to provide apparatus for use in monitoring the condition of two threads of a sewing machine by sensing the consumption of only one of said threads.

The invention will be described with reference to the figures wherein:

FIG. 1 is a schematic diagram of a presently preferred embodiment of the invention.

FIGS. 2A, 2B and 2C are signal diagrams, idealized for instructional purposes, which are useful in describing the operation of the circuit depicted in FIG. 1, and

FIG. 3 is a diagram of an operational curve for the presently preferred embodiment of the invention.

For ease of description, the apparatus of the invention is shown adapted to employ a fluid pulse train wherein the pulse durations and spacings are equisized with respect to each other, although as aforesaid this is not a requirement of the instant apparatus.

Referring to FIG. 1, a sewing machine 10 supports a journal 12 on which a pulley 14 is rotatably supported. The pulley 14 is provided with a plurality of spokes 16; and needle thread 18 from the sewing machine 10 winds on and drives the pulley 14. To prevent slipping of the thread 18 on the pulley, at least a full turn of thread 18 is placed on it, and to guide the thread 18 onto the pulley, thread guides 20, 22 are employed. As above indicated, the pulley spokes 16 are all substantially identical and are of generally the same configuration as any one spacing 24 between adjacent spokes, with the number of spokes in the pulley being directly determinative of the fineness of the control provided by the instant circuit.

A transmitting tube 26 directs a steady stream of air, provided by a source 28, at the pulley spokes 16 (or spaces 24); and a receiving tube 30 is spacially aligned to receive the transmitted air stream when the pulley 14 is so rotated that the transmitting tube 26 aligns with a pulley space 24. The transmitting and receiving tubes 26, 30 ideally are so sized that the transmitted air stream is substantially blocked from the receiving tube whenever the pulley rotation is such that a spoke aligns with the air stream; and the needle thread 18 is disposed on the pulley 14 so as not to interfere with such air stream. Therefore, when the pulley 14 is stationary, either a steady air stream, or no air stream, is directed to the receiving tube 30 depending respectively on whether a space 24 or a spoke 16 aligns with the output of the transmitting tube 26; when the pulley rotates, a train of air pulses is received by the receiving tube 30.

The output of the receiving tube 30, whether a steady air stream or not or whether a train of air pulses, is applied to the control port 32 of a monostable (Coanda) fluid amplifier 34 that is so biased at 36 that fluid applied to its input 38, at pressure P_1 , is normally, i.e. absent fluid signals at 32, directed into the output leg 40 of the amplifier. With an air pressure signal applied to the

control port 32 of the amplifier 34, however, the input fluid at 38 is switched to the output leg 42 of the amplifier.

The control port 44 of a Coanda flip-flop 46 receives the fluid output of the leg 40 of the amplifier 34, and serves to switch input fluid, of pressure P_2 , applied at 48 to the output leg 50 of the flip-flop 46. The fluid pressure signal in the flip-flop leg 50 is applied via an adjustable delay device 52 to the control port 54 of a second Coanda flip-flop 56. The delay device 52, which may take the form for example of a needle valve or an adjustable length of tubing, is so adjusted that the integrated pressure signal appearing in the output leg 58 of the flip-flop 46 is minimal when the sewing machine 10 is consuming thread 18 at its desired normal rate.

Delayed pressure signals applied to the control port 54 of the flip-flop 56 switch input fluid, of pressure P_3 , applied at 60 to the output leg 62 of the flip-flop 56. The fluid output signal of the flip-flop leg 62 is applied to the control port 64 and serves to switch the pressure P_2 fluid to the flip-flop leg 58. Fluid pressure signals appearing in the leg 42 of the amplifier 34 are applied to the control port 66 of the flip-flop 56, and serve to switch the pressure P_3 fluid to the flip-flop leg 68, whereby such P_3 fluid is exhausted from the circuit. Pressure fluid output in the leg 58 of the flip-flop 46 is applied to a pressure integrating detector element 70, e.g. a diaphragm actuator, the output of which controls a detector element which may for example be a microswitch that excites an alarm system.

To be noted from FIG. 1 is the fact that the input fluid pressures are such that pressure P_1 is less than pressure P_2 , and pressure P_2 , is less than pressure P_3 .

As to operation of the circuit of FIG. 1 for monitoring the consumption of thread by a sewing machine, the description below relates to operations under the following conditions: (1) The pulley 14 is stationary, as for example when the sewing machine needle thread 18 has broken, and a steady stream of air is transmitted to the receiving tube 30 via a pulley space 24. (2) The pulley 14 is stationary, and no air stream reaches the receiving tube, as for example when a pulley spoke 16 blocks the air stream. (3) The sewing machine is so functioning normally that the air pulses produced by means of the pulley are of a particular duration. (4) The produced air pulses are of longer duration than such particular duration, as for example when the pulley is rotating at too low a rate in response to, say, a broken bobbin thread. (5) When the pulley is rotating at too high a rate and the produced air pulses are of too short a duration.

Condition 1.—A steady stream of air from the receiving tube 30, overcomes the monostable amplifier 34 bias applied at 36, and causes the P_1 fluid to switch to the amplifier output leg 42. Fluid in the output leg 42, absent any P_2 fluid applied at 54, causes the flip-flop 56 to switch and apply its P_3 fluid to its exhaust leg 68. If P_2 fluid is being applied at this time to the flip-flop leg 58, causing the detector 70 to alarm (for zero thread consumption), it so remains because control signals are at this time applied to neither control port of the flip-flop 46: if at this time, however, pressure fluid P_2 is being applied to the flip-flop 46 output leg 50, it flows via the delay device 52 to override the P_1 pressure signal applied to the control port 66 because P_2 is greater than P_1 , and causes the P_3 pressure fluid to be applied to the flip-flop 56 output leg 62; in turn, the P_3 fluid applied to the control port 64 of the flip-flop 46 switches such flip-flop to cause the P_2 fluid to flow to the leg 58 to alarm for zero thread consumption.

Condition 2.—With no pressure applied to the amplifier 34 control port 32, the bias at 36 causes the P_1 fluid to flow to the amplifier output leg 40. This causes control fluid to be applied at 44, and causes the flip-flop 46 to switch its P_2 fluid to its output leg 50. Such P_2 fluid, via the delay device 52, gets applied to the flip-flop 56 control port 54, and causes P_3 fluid to be switched to

the flip-flop 56 output leg 62, thereby applying a control signal to the control port 64 of the flip-flop 46. This causes the flip-flop 46 to switch its P_2 fluid to its output leg 58, whereby the detector 70 alarms for zero thread consumption.

Condition 3.—See in particular FIG. 2A, which shows respective signal waveforms as they appear at the similarly noted elements of FIG. 1. With the delay device 52 properly set, as will be described hereinafter, and a "normal" pulse train 32 (as produced by a pulley 14 rotating in response to a sewing machine that is consuming thread at a normal rate) applied to the input 32 of the amplifier 34, the output legs of the amplifier 34 get excited as shown by respective waveform curves 40, 42. Since the output leg 40 of the amplifier 34 alternately is placed under P_1 pressure, the P_2 fluid is alternately switched to the flip-flop 46 output leg 50 as shown. Note that the P_2 pressure level, as shown in FIG. 2A, is greater than the P_1 pressure level. By delaying the P_2 signal waveform, appearing at 50, to coincide phasewise with the P_1 pressure signal at 42 (66) the P_1 signal at 66 is repeatedly overridden by the P_2 signal at 54, whereby P_3 pulses are repeatedly applied at 64 to effect P_2 pulses of the flip-flop 46 output leg 58. However, since the P_1 pressure pulses applied at 44 are out of phase with the pulses at 64, the flip-flop 46 leg 50 is excited as frequently as the leg 58. Because in the instant example, the pulse durations and spacings are equisized, this means that for a "normally" running pulley, the integrated pressure applied to the detector 70 is minimally one-half the P_2 pressure level, i.e. the excitation of the flip-flop 46 leg 50 is maximal. By biasing the detector to ignore integrated pressures below a certain level P_{bias} , i.e. one-half the P_2 pressure, and to alarm for integrated pressures above a certain threshold level P_T , the objects of the invention are attained. See FIG. 3.

Condition 4.—See FIG. 2B which shows a series of signal waveforms similar to those shown in FIG. 2A, but indicating that the air pulses produced by a slowly rotating pulley are of longer duration than those produced when the pulley is rotating at its "normal" rate. With long duration pulses applied to switch the monostable amplifier 34, switching signals are again produced to switch the flip-flops 46 and 56. However, since the time delay to the P_2 pressure signal appearing in the output leg 50, as provided by the delay device 52, causes the P_3 signal at 64 to be in phase periodically with the P_1 signal at 44, the P_3 signal periodically overrides the P_1 signal, thereby assuring that the flip-flop 46 leg 58 is excited for a longer time than the flip-flop 46 leg 50. Integrating the P_2 output pulses in the flip-flop leg 58 produces a steady state pressure signal above the bias pressure P_{bias} , and which, if greater than the predetermined pressure threshold P_T , effects actuation of the detector element 70. See FIG. 3.

Condition 5.—In the case where the pulley 14 is rotating at too high a speed, and the pressure pulses produced thereby are of relatively short duration as compared to pulses produced when the pulley rotates at its "normal" speed (See FIG. 2C), operation of the circuit of the invention is similar to that described with reference to Condition 4 above. That is, since the P_2 pulses at 54 here are substantially out of phase with the P_1 pulses at 66, the P_3 pulses which are applied at 64 frequently periodically override the P_1 pulses at 44. Therefore, pressure is applied for longer times to the flip-flop 46 output leg 58 than to the flip-flop leg 50. Integrating the pulsed output pressure at 58 by means of the detector element 70 results in a steady state pressure level, which if above the predetermined threshold level P_T effects actuation of the detector 70.

FIG. 3 indicates the manner in which the integrated pressure output signal varies with the speed of the sewing machine pulley, and also indicates the threshold level P_T which must be exceeded for actuation of the detector 70.

It is to be appreciated that while the curve of FIG. 3 is depicted as being generally trough-like, this may be easily changed, e.g. by so modifying the circuit of FIG. 1 that the integrator 70 connects to the flip-flop 46 output leg 50 and the operation of the integrator 70 is reversed, whereby the FIG. 3 curve will appear inverted.

With respect to the tuning of the circuit of FIG. 1, regardless of the nature or arrangement of the pulley spokes 16, or of the pulse train produced thereby, the following procedure prevails: The sewing machine 10 is operated, and while thread 18 is consumed at its normal rate, the delay device 52 is so adjusted that the integrated pressure level in the flip-flop 46 leg 58 peaks down. At this time, the circuit is properly tuned. For an embodiment employing a pulley as shown in FIG. 1, this will be when the obtained pulse delay is substantially as depicted in FIG. 2A.

While the invention has been described in its preferred embodiment it is to be understood that the words which have been used are words of description rather than of limitation and that changes within the purview of the appended claims may be made without departing from the true scope and spirit of the invention.

Having thus set forth the nature of the invention, what is claimed herein is:

1. A modulation control circuit comprising first and second fluid responsive flip-flop elements, both of which are provided with respective first and second output members and respective first and second control ports, a monostable fluid responsive element having first and second output members, the first of which is adapted to receive normally the output fluid of said monostable element, said monostable element having a control port for switching its output fluid to its second output member, means for applying the fluid of said second output member of said monostable element to said first control port of said first flip-flop element, means for applying the fluid of said first output member of said monostable element to the first control port of said second flip-flop element, means for applying the output fluid of said first output member of said first flip-flop element to the second control port of said second flip-flop element, delay means

for applying the output fluid of said second output member of said second flip-flop element to the second control port of said first flip-flop element, and means responsive to the fluid of the first output member of said second flip-flop element.

2. The apparatus of claim 1 wherein the first and second flip-flop elements and the monostable element are excited respectively by fluid at first, second and third pressures, said first pressure being greater than said second pressure, and said second pressure being greater than said third pressure.

3. The apparatus of claim 1 including means for applying a train of fluid pulses to the control port of said monostable element, and wherein said means responsive to the fluid of the first output member of said second flip-flop element is adapted to respond to averaged pressures of that fluid which are above a predetermined amount.

4. The apparatus of claim 3 wherein said means for applying a train of fluid pulses to said control port of said monostable element comprises a rotatable spoked wheel and means for so directing a stream of air at said wheel that the spokes thereof modulate said air stream.

5. The apparatus of claim 1 in conjunction with a sewing machine, said sewing machine being provided with a spoked wheel drivable by the thread thereof as said thread is consumed, means for so directing a stream of air at said wheel that said stream is modulated by said spokes when said wheel turns, means for applying the modulated air stream to the control port of said monostable element, and wherein said means responsive to the fluid of said first output member of said second flip-flop element is pressure responsive means for alarming when the average pressure of its received fluid exceeds a predetermined amount.
